UNITED STATES PATENT OFFICE.

AUGUSTUS SMITH, OF ROSELLE, NEW JERSEY, ASSIGNOR TO BERGEN POINT IRON WORKS, OF BAYONNE, NEW JERSEY, A CORPORATION OF NEW JERSEY.

WAGON.

1,253,897.

Specification of Letters Patent. Patented Jan. 15, 1918.

Application filed April 6, 1915. Serial No. 19,536.

To all whom it may concern:

Be it known that I, AUGUSTUS SMITH, a citizen of the United States of America, and residing at Roselle, in the county of Union and State of New Jersey, have invented a certain new and useful Improvement in Wagons, of which the following is a specification.

My invention relates to wagons and particularly to wagons for collecting refuse, such as ashes, garbage, or the like, the object of my invention being to provide an improved construction adapted to facilitate the dumping of the cans into the wagon and to prevent the blowing about of dust as the cans are emptied.

An illustrative embodiment of my invention is represented in the accompanying drawings in which—

20 Figure 1 is a side elevation partially broken away, showing a wagon in which my invention is illustratively embodied;

Fig. 2 is an end elevation partially in section, of the same;

25 Fig. 3 is a partial longitudinal section thereof drawn to a larger scale;

Fig. 4 is a perspective of a refuse can adapted to coöperate with the wagon;

30 Figs. 5 and 6 are side elevations of a modified can construction, with the closure hood in different positions;

Fig. 7 is a perspective thereof; and

Fig. 8 is a side elevation showing this can in dumping position.

35 In the form here shown the wagon is of the general type disclosed in my Patent 886,734 and the body 5, here in two parts, *a* and *b*, is lifted off the chassis 6 when the load is to be dumped. The means for dumping the cart as a whole forms no part of my present invention however and the construction of the cart in general is immaterial except so far as relates to the can emptying feature with which the present invention is

45 particularly concerned.

The construction now shown, is particularly designed for coöperation with a refuse can such as 7 provided with trunnions 8 at its upper margin on which the can may be rested while it is tilted to empty its contents into the cart. To support the can on these trunnions above the cart body, I provide the latter with a series of transverse tracks or slides 9 spaced apart the proper

distance to accommodate a can between each pair while at the same time affording bearings for the trunnions 8. Between each pair of slides 9, the side of the wagon is recessed at 10 to accommodate the can 7 as it is shoved in horizontally over the body of the wagon to the spot at which it is desired to empty it. This operation can readily be performed by a man standing at the side of the wagon or by an assistant on top.

The slides 9 may be of any desired construction, that shown, viz. an inverted angle bar, being simple, strong and efficient. The marginal portions of the wagon on which the cross slides 9 are mounted, may be made independent of the body 5 and secured thereto through a longitudinal angle bar 11. In this case the cross slides and their longitudinal carrying members would constitute a frame which could be made to suit any shape of wagon body to which it might be desirable to apply it.

In order to prevent the wind from scattering the contents of the cans as they are dumped, as well as from the wagon as it travels, pairs of cover flaps or shutters 12 are preferably provided. These may be hinged on rods 13 arranged in the channels of the cross slides 9. Each rod carries two cover flaps, in the construction here shown, one flap extending half way toward the adjacent cross slide on one side and the second cover flap doing the like on the other side. Each flap is preferably provided with a knuckle or knee 14 or the like which not only permits it to lie flat in covering position but also serves as a supporting stop when the flap is opened. The knee 14 also insures the closure of the adjacent flap pivoted on the same rod 13, since both cannot be opened at the same time. It thus serves to enforce the obvious rule that covers should be kept closed except when necessarily opened to receive the contents of the cans.

The wagon body which I recommend for the usual requirements of street service is 100 too wide to be conveniently filled from one side and it may be desirable to have two separately detachable bodies or compartments *a* and *b* as shown. In this case, a partition such as 15 is mounted on the wagon frame between the two compartments and is extended above the sides of the wagon perhaps a foot or so,—a sufficient distance

to coöperate with the opened cover flaps in the formation of a wind screen during the dumping of the can contents. Obviously the can itself forms a very good wind screen 5 on the fourth side of the opening which is protected on three sides by the two cover flaps and the partition 15.

Dividing the load carried by the vehicle into two compartments or bodies as above 10 described, will often be convenient because it reduces the size and cost of the dumping machine. It also makes it possible to collect and keep separate two different kinds of refuse. On the other hand it adds to the 15 cost of the vehicle and to the dead weight or tare of the latter, so that in some instances it will be preferable to provide only a single body for the vehicle. Even in such a construction I would provide the longitudinal 20 septum or partition which would then be attached to the wagon body instead of to the chassis. The covers would in like manner extend to this partition and all the wind screen and other advantages heretofore mentioned would be secured in like 25 manner. Consequently, in the subjoined claims when speaking of the body of the wagon, I use the expression in a sense broad enough to include a body in which the two 30 compartments are rigid with relation to each other as well as when they are independent, provided the context admits of such interpretation. Obviously in both constructions, the partition 15 prevents cross 35 blasts of wind above the refuse in the wagon when the cover flaps are all down and thus prevents the scattering of dust which otherwise might occur.

The can instead of having only a fixed 40 half dome as in Fig. 4, may conveniently be provided with a hinged hood 16 pivoted at 17 to the body 18 so that the fill and dump opening 19 may be closed. In this case the trunnion 20 would be mounted on the hood 45 16 eccentric to the pivot 17. When the can, resting on these trunnions 20 on the cross slides 9, is tilted up to empty its contents into the wagon, the hood 16 is automatically opened and permits the can contents to be 50 discharged. In either can construction, the trunnions are mounted substantially in vertical alinement with the lifting handles 21

so that the can is readily rested thereon when it is lifted to the slides 9.

Various modifications of details of construction will readily suggest themselves which do not depart from what I claim as my invention.

I claim as my invention:—

1. A wagon body having a longitudinal 60 partition, a series of transverse supporting members above the containing portion of the body, adapted to receive and support between adjacent members a dump can while the same is being emptied into the 65 body of the wagon, and pivoted cover flaps carried by said transverse members and co-operating, when open, with said longitudinal partition to form a wind screen while the can is being emptied into the wagon 70 body.

2. In a refuse handling system, a wagon body having a longitudinal partition and transverse supporting members, together with cover flaps on said transverse members and extending half way between adjacent members, said cover flaps coöperating, when open, with said partition to form a wind screen, substantially as described.

3. In a refuse handling system, a wagon 80 body having a longitudinal partition and transverse supporting members, together with rods arranged at each of said transverse members and pairs of cover flaps pivoted on each of said rods, the flaps on each 85 rod respectively extending partially across the spaces on opposite sides of said rod.

4. In a refuse handling system, a wagon having a containing body and a series of transverse supporting members above the 90 same, in combination with a dump can with swinging cover, said can having trunnions adapted to rest upon said transverse supporting members and means on said cover engaging said members to swing the cover 95 open on the uptilting of the can to discharge its contents into the wagon body.

In testimony whereof I have signed my name to this specification, in the presence of two subscribing witnesses.

AUGUSTUS SMITH.
